UNITED STATES PATENT OFFICE.

HOWARD HARSH, OF OSAKIS, MINNESOTA.

RAIL-FASTENING MEANS.

1,263,665.

Specification of Letters Patent. Patented Apr. 23, 1918.

Application filed July 28, 1917. Serial No. 183,257.

To all whom it may concern:

Be it known that I, HOWARD HARSH, a citizen of the United States, residing at OSAKIS, in the county of Douglas and State 5 of Minnesota, have invented certain new and useful Improvements in Rail-Fastening Means; and I do hereby declare the following to be a full, clear, and exact description of the invention, such as will enable others skilled in the art to which it appertains to 10 make and use the same.

This invention relates to new and useful improvements in rail fastening means and the primary object of the invention is to 15 provide means of this character which can be adjusted to permit of the rail being adjusted vertically and which can be further adjusted to permit of the rail being adjusted laterally in either direction.

Another object of the invention is to provide a railroad tie at each end with a pair 20 of rail fastening means, each pair of rail fastening means being adjustable with respect to each other whereby the rails can be 25 adjusted in spaced relation to each other or equally adjusted laterally in the same direction.

A further object of the invention is to provide a reversible railroad tie at each end 30 with a pair of vertically disposed casings, each adapted to receive spike holding devices which may be inserted therewith from either end of the casing and lockingly engaged therewith.

With these and other objects in view as 35 will appear as the description proceeds, the invention comprises the various novel features of construction, combination and arrangement of parts as will be more fully 40 described hereinafter, and set forth with particularity in the appended claims.

Referring to the drawings,

Figure 1 is a vertical longitudinal sectional view through a portion of the railroad tie showing my improved rail fastening means operatively associated therewith.

Fig. 2 is a transverse sectional view taken on the line 2—2 of Fig. 1.

Fig. 3 is a similar view showing the spike holder after it has been rotatably adjusted.

Fig. 4 is a vertical sectional view through the spike holder casing, and

Fig. 5 is a detail perspective view of the same.

Similar characters of reference are used 55 to denote corresponding parts throughout

the accompanying drawings and the following description.

Referring more particularly to the drawings, the reference numeral 1 indicates a railroad tie which in this instance is constructed of cement and is provided adjacent each end with a pair of vertically disposed spike holder casings 2 respectively. Each of these spike holder casings is square in cross section and is offset on three sides intermediate its ends to provide a recess 3. This offset portion serves to anchor the casing within the tie and prevent casual displacement.

An elongated spike holder 4, of square cross sectional contour, is removably positioned within each casing. Each spike holder is provided in one side with a longitudinally disposed channel 5 which is arranged adjacent one edge of said side for a purpose which will presently appear.

A latch member 6 has its lower end pivotally mounted as indicated by the numeral 7 in the channel 5 of each spike holder and is adapted to be adjusted at its upper end in and out of the channel 5 through the medium of a set screw 8 which extends therethrough. The intermediate portion of the latch member is provided with a laterally 75 projecting shoulder 9 that is adapted to lockingly engage within the recess 3.

In the operation of the device the spike holder 4 is inserted within the casing 2 and the shoulder 9 lockingly engaged within the 80 recess 3 after which the spike 10 is driven into the channel between the latch member and the bottom of the channel until the spike head rests upon the base flange of the rail 11. After the spike has been driven 85 home, the set screw 8 is turned up into engagement with the spike so as to rigidly hold it in an operative position with respect to the rail and the tie.

Should it be desired to adjust the rail vertically or shim it up, the set screws 8 can be loosened and a shim placed under the rail base and the spikes again driven home and secured in adjusted position.

On the other hand should it be desired to 105 use a rail having a base flange of greater width than the one shown, the spike holders can be removably and rotatably adjusted so that the sides indicated by the numeral 12 are nearest the rail flange, by virtue of 110 which adjustment the spikes 10 will be further removed from each other to receive the

larger rail base. By adjustably rotating the spike holders so that the sides 13 are opposed to each other, a rail having a narrower base can be accommodated there between. By rotatably adjusting the spike holders of each pair independent of each other, so that say for instance one side 12 of one spike holder and one side 13 of the other spike holder are opposed to each other, a number of adjusted combinations may be had to produce the desired lateral adjustment of the rail.

Since the recesses 3 are formed intermediate the ends of the spike holder casings, it will be manifest that the spike holders can be quickly and readily removed from the position shown, the tie reversed bottom for top and the spike holders again inserted into the casings and the shoulders 9 engaged with the recesses of the casing. It is of course to be understood that the spike holders can be rotatably adjusted, in this instance, in the same manner that they could be before the tie was reversed.

25 I claim:

1. A railroad tie comprising a pair of casings disposed vertically therethrough, a spike holder removably positioned in each of said casings, a spike removably positioned in one of said spike holders, and means for locking each of said spikes and spike holders to their respective casings.

2. A railroad tie comprising a pair of casings disposed vertically therethrough, a spike holder insertible in each of said casings from either end, means carried by each spike holder adapted to lockingly engage the intermediate portion of the casing, a spike for each spike holder, and means for locking said spike in adjusted position.

3. The combination with a railroad tie, of rail fastening means comprising a pair of casings disposed vertically through each end of said tie, a spike holder removably positioned within each casing, means for locking each spike holder in its respective casing, and means for locking a spike within each spike holder.

4. The combination with a railroad tie, of rail fastening means and means for rotatably adjusting said fastening means to permit of lateral adjustment of the rail.

5. The combination with a railroad tie,

of rail fastening means comprising spike holders removably positioned in said tie, means for rotatably adjusting said spike holders, spikes for said spike holders, and means carried by each spike holder for simultaneously locking said spike holder and spike in adjusted position.

6. The combination with a railroad tie, of rail fastening means, means for adjusting the fastening means vertically to permit of vertical adjustment of the rail, and means for rotatably adjusting said fastening means to permit of lateral adjustment of the rail.

7. A reversible railroad tie having a pair of openings disposed vertically adjacent each end, a casing arranged in each opening and provided intermediate its ends with a recess, a spike holder removably arranged within each casing and embodying a latch member, a shoulder formed on said latch member and adapted to engage the casing recess, a spike adapted to be driven in said spike holder between it and said latch member until the spike head rests upon the rail flange, and a set screw extending through said latch member and adapted to engage said spike to hold it against movement.

8. A reversible railroad tie having a pair of openings extending vertically therethrough adjacent each end, a casing disposed through each opening and formed with a recess extending around three sides thereof and disposed intermediate its ends, a spike holder arranged in each casing and embodying a latch member pivotally mounted within the spike holder, a shoulder formed on said latch member and adapted to engage the recess of said casing, a spike adapted to be driven in between the latch member and the spike holder, and a set screw extending through the free end of the latch member and adapted to engage the spike to hold it against movement, said spike holder being removably positioned within the casing to permit it to be rotatably adjusted within the casing.

In testimony whereof I have signed my name to this specification in the presence of two subscribing witnesses.

HOWARD HARSH.
